FIRE EXTINGUISHER

Charles H. Somers, Dayton, Ohio, and Sumner C. Willis, White Plains, N. Y., assignors to The Fyr-Fyter Company, Dayton, Ohio, a corporation of Ohio

Application May 16, 1950, Serial No. 162,255

13 Claims. (Cl. 169—31)

1

This invention relates to fire extinguishers, and more particularly to a fire extinguisher adapted for use with a charge of dry chemical fire extinguishing material and provided with a cartridge of compressed gas such as CO₂ for developing pressure within the extinguisher to effect discharge of the fire extinguishing material in use.

In accordance with the invention, there is provided a fire extinguisher of this character which is of simple and economical construction and which has material advantages from the standpoint of both convenience and reliability in use. In the extinguisher, a simple shell forms the container for the charge, and a separate head which is detachably secured to the shell supports all of the operating parts of the extinguisher. Instead of having the discharge hose or other outlet attached to the lower part of the shell, in the extinguisher of the present invention, the discharge hose or other outlet is directly secured to the head and is provided with a pickup tube within the container which extends downwardly from the head to a position near the bottom of the shell. The gas cartridge is also directly carried by the head, and a connecting passage in the head leads from the cartridge to a gas tube extending downwardly to the bottom of the shell to release the pressure gas at the bottom of the shell in such manner as to agitate the charge during the upward passage of the gas to the top of the container and thus to assure proper discharge of the fire extinguisher material through the pickup tube and discharge outlet.

This construction of the extinguisher with the discharge outlet at the head has been found to improve the maneuverability and manipulation of the extinguisher, and a handle is provided on the head to facilitate both carrying and use of the extinguisher. This handle also operates the piercing pin which opens the gas cartridge for initial actuation of the extinguisher, the arrangement being such that simple downward movement of the handle about its pivoted connection to the head operates the pin. In addition, when the handle is then used to lift the extinguisher for operation, the piercing pin will automatically be withdrawn from the ruptured sealing disk of the cartridge to assure free flow of gas therefrom into the container, while at the same time stops are provided on the handle and head for limiting upward movement of the handle in the proper position for ready use during operation of the extinguisher.

It is accordingly one of the principal objects of the present invention to provide a fire extinguish-

er of the above type for use with a charge of dry chemical fire extinguishing material which is simple and economical to construct, easy to use and refill, as well as reliable in operation, and wherein the head for the shell carries all of the operating parts of the extinguisher and is thus readily applicable to containers of different sizes and charge capacities.

It is also an object of the invention to provide such a fire extinguisher wherein the same handle employed for manipulation of the extinguisher during operation also serves to actuate the opening mechanism for the pressure gas cartridge, and particularly to provide such a handle which is arranged to effect automatic withdrawal of the opening pin from the cartridge during use of the extinguisher and thus to assure unimpeded flow of pressure gas into the container portion of the extinguisher for effective discharge of the charge.

Other objects and advantages of the invention will be apparent from the following description, the accompanying drawing and the appended claims.

In the drawings—

Fig. 1 is a perspective view of a fire extinguisher in accordance with the invention;

Fig. 2 is a vertical section of the extinguisher taken on the line 2—2 of Fig. 4;

Fig. 3 is an enlarged fragment of Fig. 2 showing the operation of the piercing pin for the gas cartridge;

Fig. 4 is a top plan view of the extinguisher;

Fig. 5 is a view in rear elevation of the upper portion of the extinguisher;

Figs. 6 and 7 are enlarged fragmentary sections on the lines 6—6 and 7—7 respectively of Fig. 4;

Fig. 8 is an enlarged fragmentary section on the line 8—8 of Fig. 4 showing the means for securing the head of the extinguisher to the shell; and

Fig. 9 is an enlarged fragmentary view of the neck of the gas cartridge showing the sealing disk and plug assembly for the cartridge.

Referring to the drawing, which illustrates a preferred embodiment of the invention, the shell 10 which forms the container for the charge of dry chemical fire extinguishing material includes a main cylindrical body, and an inverted bowl shaped member 11 is inserted within the lower end of the shell to form the bottom of the container. The lower rim of the shell 10 and bottom member 11 are readily secured together by welding, and an annular rubber base 12 having a channel shape in section is received over the bottom rim of the shell as shown in Fig. 2.

The upper end of the shell 10 is provided with

an annular dome 13 having a downwardly extending central flange 14 defining a large cylindrical opening 15. A reinforcing ring 16 is supported within the upper end of dome 13 by spinning over at 17 the lower edge of the flange 14. This ring 16 is provided with a plurality of tapped holes 18 as shown in Fig. 8 for receiving the mounting bolts 20 which secure the head 22 to the shell, and a gasket 23 is provided between the head 22 and dome 13 to seal this connection. A loop 24 is welded to the shell 10 to provide for hanging the extinguisher on a suitable wall bracket.

The head 22 supports all of the operating parts of the fire extinguisher, and it includes a filling opening 25 through the top thereof which is provided with a screw cap 26 and sealing ring 27. At the front of the head is a discharge opening 30 into which is threaded an elbow 31 to which the hose 33 is secured by means such as a ferrule 34. A nozzle 35 is secured to the other end of hose 33 by a ferrule 36, and the discharge passage 37 through the nozzle is controlled by a pin 40 which forms a slide valve and is controlled by a handle 41 pivoted to the nozzle at 42 and provided with a spring 44 which normally urges the handle to the closed position of the valve pin 40. A pickup tube 45 is secured within the inside end of the discharge opening 39 in head 22, and this tube extends downwardly within the container to a position near the bottom and one side of the container and well below the upper end of the bottom member 11 as shown in Fig. 2.

A spring clip 46 may be welded or otherwise secured to the side of the shell 10 for holding the nozzle during non-use of the extinguisher. Also, in order to prevent foreign matter from entering and possibly clogging the discharge passage 37 when the extinguisher is not in use, a rubber protector cap 47 is frictionally fitted over the end of the nozzle and is secured to shell 10 by a chain 48. Thus when the nozzle is removed from clip 46, the chain 48 will automatically pull cap 47 from the nozzle to make it ready for use.

The gas cartridge 50 is provided with a threaded neck portion 51 which is received within a tapped socket 52 in the under side of a rearwardly projecting extension portion 53 of head 22. The upper surface of this head portion 53 is formed with a depression 54, and two drainage holes 55 are accordingly provided therethrough as shown in Figs. 4 and 7. A flat nut 56 is welded to the upper end of the cartridge to facilitate tightening of the threaded neck 51 in socket 52, and a rubber gasket 57 is provided between the end of the cartridge and the base of the socket. The cartridge is also provided with a supporting clip 58 secured to the back of the shell 10.

A vertical passage 60 connects the socket 52 with the horizontal passage 61 which extends radially inwardly of the head to a position located inwardly of the central opening 15 in dome 13, and the under side of the head is formed with an annular boss 62 at the inner end of this passage 61, the outer end of passage 61 being sealed by a plug 63. A tube 64 is inserted within the lower end of boss 62, and this tube extends downwardly and is bent in such manner as shown in Fig. 2 that its lower end is located at the opposite side of the shell from the lower end of the pickup tube 45 and well below the upper end of the bottom member 11. Thus when the gas cartridge 50 is opened, the gas will pass therefrom through the socket 52 and passage

60 to the passage 61 and then through the boss 62 and tube 64 to the bottom of the container for discharge into the interior of the container.

5 A sealing disk and plug assembly shown in detail in Fig. 9 is secured within the neck 51 of cartridge 50. This assembly includes an annular plug 65 having threads along the upper part of its outer surface for engagement within the tapped inner portion of the cartridge neck 51, and the inner part of this plug is provided with vertical slits 66 for receiving a suitable wrench. A thin sealing disk 70 of brass or other suitable material is mounted within plug 65 between an annular insert 71 and an annular retainer 72, and these parts are secured within the plug by spinning over the thin lower end portion of the plug as indicated at 73. The neck of the cartridge is provided with an annular boss 74 against which the retainer 72 seats as shown in Fig. 9, and the disk 70 serves to seal the interior of cartridge 50 and is adapted to be ruptured to effect release of the pressure gas for actuating the extinguisher.

10 A handle 75 serves both as a carrying handle for the fire extinguisher and also as the operating member for effecting opening of the gas cartridge 50 by rupture of the sealing disk 70. The forward end of this handle is pivoted to the head 22 by means of a stud 76 which is threaded into the head and is connected with the handle by means of a pivot pin 77 supported in a yoke portion 78 at the front of the handle. At the rearward end of the handle is a downwardly extending portion 80 which is received between the channelled outer end 81 of the head extension 30 35 53 for guiding the handle in its pivotal movement about the pivot pin 77.

25 The handle 75 supports a piercing pin 85 for opening the gas cartridge, this pin extending slidably through a bore 86 in the head 22 and into the passage 60 and socket 52. The upper end of the bore 86 is sealed by an O-ring 87 compressed against the bottom of a socket 88 in the upper surface of the head 22 by a retainer nut 89. The upper end of pin 85 is pivoted by a pin 90 in a yoke portion 91 of handle 75, the yoke 91 being slotted at 92 to receive pin 90 and thus to provide for the angular movement of the handle about its pivot 77 with respect to the piercing pin. It will thus be seen that when the handle 75 is moved downwardly about its pivot 77, it will move the piercing pin 85 downwardly to effect rupture of the sealing disk 70 and release of the contents of cartridge 50 into the passages 60 and 61. The retainer 89 and bore 86 guide pin 85 during this movement to maintain it in proper alignment with the neck of cartridge 50 and the sealing disk 70, and in order to prevent water or dirt from entering around pin 85 when the extinguisher is not in use and possibly causing it to stick, a flexible rubber cover 93 is provided as shown in Figs. 2 and 3, which fits between the head of pin 85 and an annular boss 94 on the head and is compressed like a diaphragm when handle 75 is depressed.

cartridge, the seal 100 being readily broken when the extinguisher is to be used. In addition, stops are provided for limiting upward movement of the handle about pivot 77 when the locking pin 95 is not in place. Referring to Figs. 5 and 6, the lower end of the handle portion 80 is formed with laterally projecting ears 101 and the inner faces of the channelled portion 81 of the head is under cut at 102 to provide shoulders which cooperate with ears 101 to form stops limiting upward movement of the handle.

Fig. 2 shows the extinguisher in normal condition ready for use, with the charge of dry chemical fire extinguishing material indicated at 105. For example, a suitable material for use with this extinguisher is a powder composed primarily of sodium bicarbonate. In order to operate the extinguisher, the locking pin 95 is first withdrawn, and the handle 75 is then pushed downwardly to force the lower end of the piercing pin 85 through the sealing disk 70 as shown in Fig. 3. Upon the resulting rupture of this disk, the gas within the cartridge 50 will be released through the passages 60 and 61 to the tube 64, and the gas will thus be released at the bottom of the charge and will percolate upwardly through the dry material, thus agitating the charge in preparation for discharge. As soon as sufficient gas has reached the top of the shell to create the desired pressure on the charge, which requires only a few seconds, the handle 41 on the nozzle is operated to pull the valve pin 40 to open position and permit free discharge of the fire extinguishing material. It will be noted that during this operation of the extinguisher, since the gas is released from tube 64 at the opposite side of the shell from the lower end of the pickup tube 45, and since both of these tubes extend downwardly to positions well below the upper end of the bottom member 11, the latter serves to seal against possible short circuiting of the gas to the pickup tube and assures full and proper discharge of substantially the entire contents of the shell.

The handle 75 can be readily used for manipulation of the extinguisher as soon as it has been operated to open the gas cartridge. In addition, the action of lifting the extinguisher by the handle will automatically effect withdrawal of the lower end of the piercing pin from the ruptured sealing disk, thus preventing possible interference by the pin with the free discharge of the pressure gas. As noted, this upward movement of the handle is limited by contact of the ears 101 thereon with the stops 102, and these parts are proportioned to position the handle at the proper level for convenient manipulation of the extinguisher.

After the charge of fire extinguishing material has been exhausted, the extinguisher is readily recharged by first inverting it and holding the nozzle open until all of the gas pressure within is released. The cap 26 for the filling opening 25 is then removed and a fresh charge of fire extinguishing material placed within the shell, and the spent cartridge 50 is unscrewed from the head and replaced with a fresh cartridge. Before replacing the cartridge, the handle 75 should be locked in its upward position by inserting the safety pin 95 in order to prevent the possibility of inadvertent rupture of the sealing disk in the fresh cartridge.

It will thus be seen that the present invention provides a fire extinguisher for use with a charge of dry chemical fire extinguisher material

which is simple to construct, easy to fill and refill, and convenient to use. The provision of a head as described which carries all of the operating parts of the extinguisher separately from the shell offers several practical advantages. Construction of the shell itself is simplified, and also the same head can be employed with shells of different capacities, the only modification required being to lengthen the pickup tube and the gas tube within the shell. It has also been found in practice that the extinguisher is handled with considerably more ease and convenience when the discharge hose is connected with the head of the extinguisher rather than at a lower position on the shell. The simple and convenient arrangement of a single handle for actuating the extinguisher has also been found highly advantageous both from the standpoint of convenience and also from the standpoint of assuring rapid and effective operation as a result of the automatic withdrawal of the piercing pin from the neck of the gas cartridge following rupture of the sealing disk. Since the primary requirement for any fire extinguisher is that it operate rapidly and effectively, and also that it be readily handled during use, it will be seen that all of these several features contribute to accomplishment of the primary purposes of the extinguisher.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A fire extinguisher adapted for use with a charge of dry chemical fire extinguishing material and a cartridge of compressed gas, comprising a shell forming a container for said charge, a head secured to the upper end of said shell, means forming a discharge outlet through said head from said container, a pickup tube for said discharge outlet secured to said head and extending downwardly therefrom within said container to the lower end of said shell, means on said head outside said shell for detachably supporting said cartridge providing for removal and replacement of said cartridge from outside said container without removing said head from said shell, means forming a passageway within said head for conducting gas from said cartridge to the interior of said container, means on said head for effecting opening of said cartridge to release said gas into said passageway, and a tube secured to said head in communication with said passageway and extending downwardly within said container to the lower end of said shell for conducting said gas from said cartridge to the bottom portion of said charge within said shell.

2. A fire extinguisher adapted for use with a charge of dry chemical fire extinguishing material and a cartridge of compressed gas, comprising a shell forming a container for said charge, a head for the upper end of said shell, means forming a discharge outlet through said head from said container, a pickup tube for said discharge outlet secured to said head and extending downwardly therefrom within said container to the lower end of said shell, means on said head outside said shell for supporting said cartridge providing for removal and replacement of said cartridge from outside said container

without removing said head from said shell, means forming a passageway within said head for conducting gas from said cartridge to the interior of said container, means on said head for effecting opening of said cartridge to release said gas within said passageway, a tube secured to said head in communication with said passageway and extending downwardly within said container to the lower end of said shell for conducting said gas from said cartridge to the bottom portion of said charge, and means for releasably securing said head to said shell to provide for removal of said head and said tubes and cartridge as a unit from said shell.

3. A fire extinguisher adapted for use with a charge of dry chemical fire extinguishing material and a cartridge of compressed gas, comprising a shell forming a container for said charge, a head for the upper end of said shell, means forming a discharge outlet through said head from said container, a pickup tube for said discharge outlet secured to said head and extending downwardly therefrom within said container to the lower end of said shell, means on said head outside said shell for supporting said cartridge providing for removal and replacement of said cartridge from outside said container without removing said head from said shell, means forming a passageway within said head for conducting gas from said cartridge to the interior of said container, means on said head for effecting opening of said cartridge to release said gas into said passageway, and a tube secured to said head in communication with said passageway and extending downwardly within said container to the lower end of said shell for conducting said gas from said cartridge to the bottom portion of said charge, means for releasably securing said head to said shell to provide for removal of said head and said tubes and cartridge as a unit from said shell, said head having a filling opening therein for recharging said container, and a cap removably secured to said opening to provide for charging said container without removing said head from said shell.

4. A fire extinguisher adapted for use with a charge of dry chemical fire extinguishing material and a cartridge of compressed gas, comprising a shell forming a container for said charge, a head secured to the upper end of said shell, means forming a discharge outlet through said head from said container, a pickup tube for said discharge outlet secured to said head and extending downwardly therefrom within said container to the lower end of said shell and at one side thereof, means on said head for supporting said cartridge, means on said head for effecting opening of said cartridge to release said gas within said container, and a tube secured to said head in communication with said cartridge and extending downwardly within said container to a position at the lower end of said shell adjacent the opposite side of said shell from the lower end of said pickup tube for conducting said gas from said cartridge to the bottom portion of said charge at a position spaced from the lower end of said pickup tube.

5. A fire extinguisher adapted for use with a charge of dry chemical fire extinguishing material and a cartridge of compressed gas, comprising a generally cylindrical shell forming the container for said charge, an inverted bowl shaped member secured within the lower end of said shell to form the bottom of said container and extending upwardly therein, a head secured

to the upper end of said shell, a discharge tube secured to said head outwardly of said shell, a pickup tube for said discharge tube secured to said head and extending downwardly therefrom within said container to a position at one side of said shell below the level of the upper end of said bottom, means on said head for supporting said cartridge, means on said head for effecting opening of said cartridge to release said gas within said container, and a tube secured to said head in communication with said cartridge and extending downwardly within said container to a position below the upper end of said bottom and at the opposite side of said shell from the lower end of said pickup tube for conducting said gas from said cartridge to the bottom portion of said charge with the upper portion of said bottom forming a shield between the discharge end of said gas tube and the pickup end of said pickup tube to prevent direct passage of said gas from said gas tube to said pickup tube.

6. A fire extinguisher adapted for use with a charge of dry chemical fire extinguishing material and a cartridge of compressed gas, comprising a shell forming a container for said charge, a head for the upper end of said shell, means forming a discharge outlet through said head from said container, a pickup tube for said discharge tube secured to said head and extending downwardly therefrom within said container to the lower end of said shell, means on said head for supporting said cartridge, means on said head for effecting opening of said cartridge to release said gas within said container, a tube secured to said head in communication with said cartridge and extending downwardly within said container to the lower end of said shell for conducting said gas from said cartridge to the bottom portion of said charge, a reinforcing ring secured within the upper end of said shell, said ring having a plurality of tapped holes therethrough, and a plurality of bolts extending through said head for engagement in said tapped holes to secure said head to said shell and provide for removal of said head with said tubes and cartridge as a unit from said shell.

7. A fire extinguisher adapted for use with a charge of dry chemical fire extinguishing material and a cartridge of compressed gas, comprising a shell forming a container for said charge, a head secured to the upper end of said shell, means forming a discharge outlet from said container, means on said head outside said shell for supporting said cartridge providing for removal and replacement of said cartridge from outside said container without removing said head from said shell, means forming a passageway within said head for conducting gas from said cartridge to the interior of said container, a tube secured to said head in communication with said passageway and extending downwardly within said container to the lower end of said shell for conducting said gas from said cartridge to the bottom portion of said charge, a handle secured to said head for carrying said extinguisher, and means carried by said head for operation by said handle to open said cartridge and to effect release of said gas into said passageway and discharge of said charge through said outlet.

8. A fire extinguisher adapted for use with a charge of dry chemical fire extinguishing material and a cartridge of compressed gas, comprising a shell forming a container for said charge, a head secured to the upper end of said shell,

means forming a discharge outlet from said container, means on said head for supporting said cartridge, a handle pivoted at one end to said head, means carried by said handle for effecting opening of said cartridge upon downward movement of said handle about said pivot therefor to effect release of said gas within said container and discharge of said charge through said outlet, and means limiting upward movement of said handle about said pivot to provide for supporting said extinguisher by means of said handle during discharge of said charge.

9. A fire extinguisher adapted for use with a charge of dry chemical fire extinguishing material and a cartridge of compressed gas, comprising a shell forming a container for said charge, a head secured to the upper end of said shell, means forming a discharge outlet from said container, means on said head for supporting said cartridge, a handle pivoted at one end to said head, a piercing pin carried by said handle in position to effect opening of said cartridge upon downward movement of said handle about said pivot therefor to release said gas within said container, said pin being adapted to be withdrawn from said cartridge upon upward movement of said handle about said pivot to assure free discharge of said gas from said cartridge into said container, and cooperating means on said handle and said head for limiting said upward movement of said handle to provide for carrying said extinguisher by means of said handle and directing the discharge thereof.

10. A fire extinguisher adapted for use with a charge of dry chemical fire extinguishing material and a cartridge of compressed gas, comprising a shell forming a container for said charge, a head secured to the upper end of said shell, means forming a discharge outlet from said container through the front of said head, said head including an extension projecting rearwardly therefrom in overhanging relation with said shell, means on said extension for supporting said cartridge, a handle pivoted at one end to said head and extending rearwardly from said pivot therefor in overhanging relation with said head extension, a piercing pin carried by said handle for effecting opening of said cartridge upon downward movement of said handle about said pivot to release said gas within said container, the rearward end of said head extension including a channelled portion for guiding said movement of said handle, said handle including a portion received within said channel, laterally projecting ears on said handle portion, and means within said channel forming stops for engagement with said ears to limit upward movement of said handle about said pivot, said ears and said stop means being proportioned to provide for sufficient upward movement of said handle to withdraw said pin from said cartridge for free release of said gas while retaining said handle in position for ready use as a handle for carrying said extinguisher during discharge of said charge.

11. A fire extinguisher adapted for use with a charge of dry chemical fire extinguishing material and a cartridge of compressed gas, comprising a shell forming a container for said charge, a head secured to the upper end of said shell, means forming a discharge outlet from said con-

60
70

tainer, means on said head for supporting said cartridge, a handle pivoted at one end to said head, a piercing pin carried by said handle slideable through a portion of said head to effect opening of said cartridge upon downward movement of said handle about said pivot therefor to release said gas within said container, and an annular sealing member receiving said pin therethrough and positioned between said handle and said head to prevent dirt and liquid from access to said pin tending to interfere with operating movement of said pin, said sealing member being flexible for compression between said handle and head upon downward movement of said handle.

12. A fire extinguisher adapted for use with a charge of dry chemical fire extinguishing material and a cartridge of compressed gas, comprising a shell forming a container for said charge, a head secured to the upper end of said shell, means forming a discharge outlet from said container, means on said head for supporting said cartridge, a handle pivoted at one end to said head, means carried by said handle for effecting opening of said cartridge upon downward movement of said handle about said pivot therefor to effect release of said gas within said container and discharge of said charge through said outlet, said handle and said head having holes therethrough adapted to register with each other when said handle is in a raised position thereof, and a removable locking member adapted to be received through said holes to prevent accidental downward movement of said handle and resulting in accidental opening of said cartridge.

13. A fire extinguisher adapted for use with a charge of dry chemical fire extinguishing material and a cartridge of compressed gas, comprising a shell forming a container for said charge, a head secured to the upper end of said shell, means forming a discharge outlet from said container, means on said head for supporting said cartridge, a handle pivoted at one end to said head, means carried by said handle for effecting opening of said cartridge upon downward movement of said handle about said pivot therefor to effect release of said gas within said container and discharge of said charge through said outlet, said handle and said head having holes therethrough adapted to register with each other when said handle is in a raised position thereof, and a sealing member adapted to be received through said locking member and through a portion of said cartridge to prevent tampering with said extinguisher, said sealing member including a readily frangible portion to facilitate removal thereof for operation of said extinguisher.
